DOMINO-ACTION TOY OR SIMILAR ARTICLE

Harry Meth and Allen Greenberg, Cincinnati, Ohio, assignors to General Mills Fun Group, Inc., Minneapolis, Minn.

Continuation of abandoned design applications Ser. No. 15,586 and Ser. No. 15,587, both Jan. 31, 1969. This application Oct. 12, 1970, Ser. No. 25,449

Term of patent 14 years

Int. Cl. D21—01

U.S. Cl. D34—15

FIG. 1

FIG. 2

FIG. 3

FIG. 4

FIG. 5

FIG. 6

FIG. 1 is a perspective view of a domino-action toy or similar article showing our new design;

FIG. 2 is a front side elevational view thereof, the opposite side being a mirror image thereof;

FIG. 3 is a top plan view of FIG. 1;

FIG. 4 is a bottom plan view thereof;

FIG. 5 is an end elevational view of FIG. 2 as taken from line 5—5;

FIG. 6 is an end elevational view of FIG. 2 as taken from line 6—6;

FIG. 7 is a perspective view of another form of a domino-action toy or similar article wherein the base is curved and has nine "dominos" thereon;

FIG. 8 is a top plan view of FIG. 7;

FIG. 9 is a bottom plan view thereof;

FIG. 10 is a front elevational view of FIG. 8 as taken from line 10—10;

FIG. 11 is a rear elevational view of FIG. 8 as taken from line 11—11;

FIG. 12 is a partial end elevational view of FIG. 8 as taken from line 12—12; and

FIG. 13 is a partial end elevational view of FIG. 8 as taken from line 13—13.

This application is a continuation of our prior design applications, Ser. No. D. 15,586, filed on Jan. 31, 1969, and Ser. No. D. 15,587, filed on Jan. 31, 1969, both now abandoned.

We claim:

The ornamental design for domino-action toy or similar article, as shown and described.
